METHOD OF CLEANING FLUES OR THE LIKE
WHICH CONDUCT PRODUCER GAS

August Reiss, London, England

Application November 5, 1942, Serial No. 464,692
In Great Britain November 17, 1941

7 Claims. (Cl. 110—1)

1

The present invention relates to method and means for cleaning flues, pipelines, valves or the like which conduct producer gas. In the specification and appended claims, under the term "producer gas" shall be understood non-purified gas which contains tar products and/or other similar combustible impurities, and incombustible impurities such as dust. When the flues or the like are in use, the combustible and incombustible impurities are deposited and choke the flues or the like if not removed.

It is an object of the present invention to effect the cleaning of flues, pipelines, valves or the like which conduct producer gas in a simple and effective manner.

It is another object of the present invention to facilitate the cleaning of the flues or the like without it being necessary to shut down and cool down the whole plant.

It is a more specific object of the invention to provide a method and means for burning efficiently the combustible impurities deposited in the flues or the like to convert them into ash, and to remove the ash together with the incombustible impurities such as dust in a simple way.

Other objects and advantages of the invention will become apparent from the subjoined detailed description taken in conjunction with the accompanying drawings, which are given by way of example only, and in which—

Fig. 1 shows a diagrammatic plan view of a plant according to this invention;

Fig. 2 is a longitudinal section through part of an underground flue for conducting producer gas;

Fig. 3 is a section along the line III—III of Fig. 2;

Fig. 4 is a section through part of an overhead flue for conducting producer gas;

Fig. 5 is a section along the line V—V of Fig. 4;

Figs. 6 and 7 illustrate in elevation and plan view an arrangement for removing the ash and incombustible impurities from an underground flue;

Fig. 8 illustrates an overhead flue showing means for removing the ash and the like therefrom;

Fig. 9 shows an overhead flue and an underground flue having a common collector for the ash and the like;

Fig. 10 shows an arrangement in which a valve is provided in the flue and is cleaned in the same manner as the flue, and

Fig. 11 shows the valve of Fig. 10 in greater detail.

Referring first to Fig. 1, the numeral 1 indi-

2

cates a plant for generating producer gas. The plant 1 is connected to a furnace, boiler or a similar consumer 2 of the producer gas by means of a flue or pipe line 3 provided with manholes 4 and 5 and explosion doors 8. In the flue or pipe line 3, groups of stationary blowers 5 are provided at the bottom of lowermost part of the flue or pipe line, the blowers of each group being interconnected by tubes 6 and connected to a steam supply valve 7, and to a compressed air supply valve 9. A chimney 10 is connected by means of a duct 11 to the consumer 2 and may be disconnected therefrom by means of a damper 111. The chimney 10 is connected through a by-pass 13 to the flue 3 and may be disconnected therefrom by a damper 14. Further blowers 15 are provided in the by-pass 13 and are connected to a steam supply valve 16 and a compressed air supply valve 17. Steam can be fed to the steam supply valves 7 and 16 from a common steam supply source (not shown), and compressed air can be fed to the compressed air supply valves 9 and 17 from a common source (not shown) of compressed air. The consumer 2 may be disconnected from the flue or pipe line 3 by means of a damper 112.

In normal operation of the plant, the manholes 4 and explosion doors 8 are closed, the damper 14 is closed and the dampers 111 and 112 are more or less opened according to requirements. Thereby the chimney 10 communicates with the consumer 2 and is disconnected from the by-pass 13. Thus, producer gas can be freely conducted from the plant 1 through the flue 3 to the consumer 2.

When it is desired to clean the flue 3 at least one of the manholes 4 and/or one of the explosion doors 8 are opened, the damper 14 is opened and the dampers 111 and 112 are shut so that the chimney 10 communicates with the by-pass 13 and thus with the flue 3 but is disconnected from the consumer 2 which in turn is disconnected from the flue 3. Steam under pressure is fed to the blowers 5 and 15 through the steam supply valves 7 and 16 respectively, and is blown by the blowers through the flue 3, the by-pass 13, and up the chimney 10. Thereby the deposit composed of tar and the like and of the incombustible impurities in the flue 3 is stirred up. At the same time, the blowers create an injector action where-

50 by air in sufficient quantity is drawn into the flue 3 through the manholes 4 and/or explosion doors 8 and is mixed intensively with the deposit of tar and the like. By this action, the tar and the like, which has a high temperature, ignites, and is completely burned and converted into ash with-

out leaving any combustible residue. Simultaneously with the burning the ash and other combustible matter in the flue 3, is blown up the chimney 10, whereby the flue 3 is cleaned.

It will be appreciated that owing to the induced draught created by the blowers the burning is completely effected within a few minutes.

Modifications of the arrangement and of the cleaning process just described are possible. For example, if it is difficult or inconvenient to open the manholes 4 and/or explosion doors 8, they may remain closed during the cleaning process. In this case, at least one of the groups of blowers is fed with compressed air through its compressed air supply valve 9 instead of with steam. Thus, compressed air and steam are simultaneously blown into the flue to create a draught therein, which enables the combustible matter to be stirred up and to burn without the necessity to admit outside air through manholes or the like. The dust and ash is blown up the chimney as before.

In any case the supply of steam may be interrupted after the deposit has been stirred up and ignited, and compressed air instead of steam may be blown through the flue to maintain the burning process. Still alternatively a mixture of steam and air may be blown through the flue. In any case, by properly adjusting the amount of steam and/or compressed air blown through the flue in a given time the burning can be slowed down so as not to overheat the walls of the flue if they are liable to be damaged by extensive heat, as is the case when they are made of steel.

Figs. 2 and 3 show detailed sections through a part of an underground flue for conducting producer gas. Numeral 40 indicates the ground level, numeral 41 the wall of the flue, numeral 42 the stationary blowers arranged at the bottom of the flue and interconnected by tubes 43 which are covered by fireclay tiles 44. The tube 45 connects the tubes 43, and thus the blowers 42, to a steam supply valve 46 and to a valve 47 for supplying compressed air to the blowers 43. The tube 45 is covered by fireclay tiles 48. It will be seen that with this arrangement steam, or compressed air, or a mixture of both may be blown through the flue by means of the same blowers, so that according to requirements in a particular case either steam, or a mixture of steam and compressed air, or only compressed air may be blown through the flue as described hereinbefore with reference to Fig. 1. In any case, the amount of steam and/or compressed air blown through the flue in a given time may be adjusted by the valves 46 and 47, and thus the burning process may be effectively controlled.

Figs. 4 and 5 show detailed sections through a part of an overhead flue for conducting producer gas. Numeral 51 indicates the wall of the flue, numeral 52 the stationary blowers arranged at the lowermost part or bottom of the flue and interconnected by tubes 53 which are covered by fireclay tiles 54. The tube 55 connects the tubes 53, and thus the blowers 52, to a steam supply valve 56 and a valve 57 for supplying compressed air to the blowers 52, which valves allow the burning process to be controlled according to requirements in the same way as explained with reference to Figs. 1, 2 and 3.

It is not necessary for the ash and dust to be blown up a chimney as shown in Fig. 1. The ash and dust may be removed in many other ways. Figs. 6 and 7 illustrate, by way of example, such an alternative arrangement for removing

the ash created by the burning process and the dust from an underground flue 60 connecting a plant 1 for generating producer gas to a plurality of consumers 2. The stationary blowers arranged at the bottom of the main flue 60 are indicated by the numeral 61 and those in the branch flues 601 which connect the consumers 2 to the main flue 60 by the numeral 611. The blowers are arranged in groups, the groups being supplied with steam and/or compressed air through steam supply valves 62 and compressed air supply valves 621 by means of tubes 63. According to requirements, either all the groups may be supplied with steam, or all the groups may be supplied with compressed air, or at least one of the groups may be supplied with steam and at least one other with compressed air. A damper 64 normally separates the flue 60 from a pit 65, while dampers 641, which are normally more or less open allow the consumers 2 to be separated from the branch flues 601 and thereby from the main flue 60. When it is intended to clean the flues 60 and 601 the damper 64 is opened so that the pit 65 communicates with the flue 60 and the dampers 641 are shut. The blowers 61 and 611 are operated and blow according to requirements, steam or compressed air or a mixture of both through the flues 60 and 601 towards the pit 65. The deposit is thereby stirred up, ignited, and burnt in the manner hereinbefore described, and the ash and dust are blown into the pit 65 which is provided with a vent pipe 66 for equalizing the excess pressure which otherwise would be created in the pit by the action of the blowers 61 and 611. The ash and dust collected in the pit are subsequently removed therefrom in any convenient manner. They may, for example, be sucked off by a pump 67 connected to a suction nozzle 68, and may be collected outside the flue at ground level as indicated at 69 (Fig. 6). Alternatively, the pit 65 may be emptied manually from the outside.

In Fig. 8, an overhead flue or pipe line 70 is illustrated which connects a plant 1 for generating producer gas through a duct 701 and a dust catcher 73 to a consumer 2. The dust catcher 73 is provided with a vent pipe 73 which is normally closed by a damper 79. The stationary blowers 71 arranged at the bottom of the flue are supplied with steam and/or compressed air through steam supply valves 72 and compressed air supply valves 721. The damper 76 is normally open. When it is intended to clean the flue 70, the damper 76 is shut and the damper 79 opened and steam and/or compressed air is blown by the blowers 71 through the flue 70 towards the dust catcher 73, the vent pipe 73 which is now open preventing any excess pressure being created in the dust catcher 73 by the blowers. Thereby the deposit is stirred up, the combustible deposit is burnt and the ash and dust are blown into the dust catcher 73, which is emptied into a truck or the like 74.

Fig. 9 illustrates an overhead flue 80 and an underground flue 81, connecting a plant 1 for generating producer gas to a consumer 2. Each flue is provided with blowers 82 and 83 respectively which are stationary and arranged at the bottom of each flue in groups and supplied with steam and/or compressed air through steam supply valves 84 and 841 and compressed air supply valves 85 and 851. The overhead flue 80 and the underground flue 81 are connected to a common ash and dust collector 88. The dust collector is provided with a vent pipe 86 which is normally closed by a damper 87. To clean the flues 80

and 81, the damper 81 is opened and the blowers 82 and 83 are actuated, to blow steam and/or compressed air through the flues 80 and 81 into the dust collector 88. The vent pipe 86, which is now open, prevents any excess pressure being created in the dust collector 88 by the blowers. Thereby, the deposit in the flues is stirred up, the combustible deposit is burnt, and the ash and dust are blown into the collector 88. In the flue 80 the blowing is done in the same direction as the producer gas normally flows, while in the flue 81 it is done in the direction opposed to the normal gas flow. A door or the like 89 enables the ash and dust to be removed from the collector 88.

In Fig. 10, a plant 1 for generating producer gas is connected to a consumer 2 by means of an overhead flue 90 and an underground flue 91. In the flue 90 at the bottom thereof stationary blowers 93 are provided. The flue 90 may be opened at 94 to admit air from the outside. Between the flues 90 and 91 a valve generally denoted by numeral 95 is interposed for regulating the flow of producer gas. The valve 95 includes a valve member 96 (see also Fig. 11) which may be displaced from its raised, open, position into the position 961, indicated in Fig. 11 in dashed lines, in which position the valve is completely shut. A shutter 97 allows the valve casing to be opened so that the interior of the valve may communicate with the outside air. Normally the shutter 97 is closed. One or several blowers 98 are provided within the valve and allow steam and/or compressed air to be blown through the valve. When it is intended to clean the flue 90 and the valve 95, the flue is opened at 94 and the valve at 97. For example, steam is blown by the blowers 98 and 93 through the valve 95 and the flue 90. Air is drawn into the valve 95 and the flue 90 at 97 and 94 and an induced draught is created. Thereby the deposit in the valve and flue is stirred up, the combustible deposit is burnt, and the ash and incombustible deposit are blown out of the valve 95 and flue 90, and are collected at 99 from where they can be removed through a door 100.

In all the arrangements described, if compressed air is blown through the flue, pipeline, valve or the like, preferably hot air is used in order to facilitate the burning of the combustible matter.

In the appended claims the expression "flue" shall also embrace a pipeline, valve and the like.

I claim:

1. A method for removing a deposit of combustible and non-combustible impurities from a flue having an outlet, comprising the steps of admitting a medium containing oxygen which is available for combustion to the flue, stirring up and loosening the deposit of impurities by forcing a gaseous fluid through the space occupied by said deposit, causing a mixing of said gaseous fluid with said oxygen containing medium, burning within the flue the combustible impurities in the presence of said oxygen containing mixture thus obtained and converting said combustible impurities into ash, and blowing said ash and the non-combustible impurities out of the flue by forcing the gaseous fluid toward the outlet in the flue.

2. A method for removing a deposit of combustible and non-combustible impurities from a flue having an outlet, comprising the steps of admitting a medium containing oxygen which is available for combustion to the flue, stirring up

and loosening the deposit of impurities by forcing a gaseous fluid through the space occupied by said deposit along substantially the entire length of the flue, causing a mixing of said gaseous fluid with said oxygen containing medium, burning within the flue the combustible impurities in the presence of said oxygen containing mixture thus obtained and converting said combustible impurities into ash, and blowing said ash and the non-combustible impurities out of the flue by forcing the gaseous fluid toward the outlet in the flue.

3. A method for removing a deposit of combustible and non-combustible impurities from a flue having an outlet, comprising the steps of admitting outside air to the flue, stirring up and loosening the deposit of impurities by forcing a gaseous fluid through the space occupied by said deposit, causing a mixing of said gaseous fluid with said outside air, burning within the flue the combustible impurities in the presence of said mixture of gaseous fluid and outside air thus obtained and converting said combustible impurities into ash, and blowing said ash and the non-combustible impurities out of the flue by forcing the gaseous fluid toward the outlet in the flue.

4. A method for removing a deposit of combustible and non-combustible impurities from a flue having an outlet, comprising the steps of admitting a medium containing oxygen which is available for combustion to the flue, stirring up and loosening the deposit of impurities by forcing steam through the space occupied by said deposit, causing a mixing of said steam with said oxygen containing medium, burning within the flue the combustible impurities in the presence of said oxygen containing mixture thus obtained and converting said combustible impurities into ash, and blowing said ash and the non-combustible impurities out of the flue by forcing the gaseous fluid toward the outlet in the flue.

5. A method for removing a deposit of combustible and non-combustible impurities from a flue having an outlet, comprising the steps of stirring up and loosening the deposit of impurities by forcing a gaseous fluid containing oxygen which is available for combustion through the space occupied by said deposit, burning within the flue the combustible impurities in the presence of said oxygen containing gaseous fluid and converting said combustible impurities into ash, and blowing said ash and the non-combustible impurities out of the flue by forcing the oxygen containing gaseous fluid toward the outlet in the flue.

6. A method for removing a deposit of combustible and non-combustible impurities from a flue having an outlet, comprising the steps of stirring up and loosening the deposit of impurities by forcing a mixture of steam and compressed air through the space occupied by said deposit, burning within the flue the combustible impurities in the presence of the compressed air of said mixture and converting said combustible impurities into ash, and blowing said ash and the non-combustible impurities out of the flue by forcing the mixture of steam and compressed air toward the outlet in the flue.

7. A method for removing a deposit of combustible and non-combustible impurities from a flue having an outlet, comprising the steps of stirring up and loosening the deposit of impurities by forcing a mixture of steam and compressed air through the space occupied by said deposit, burning within the flue the combustible

impurities in the presence of the compressed air of said mixture and converting said combustible impurities into ash, adjusting the ratio of steam to compressed air in the mixture thereof so as to prevent overheating of the flue during the burning process, and blowing said ash and the non-combustible impurities out of the flue by forcing the mixture of steam and compressed air toward the outlet in the flue.
